(57) **CLAIM**

The ornamental design for a combination respiratory mask and heat and moisture exchanger unit, as shown and described.

DESCRIPTION

FIG. 1 is a front perspective view of a combination respiratory mask and heat and moisture exchanger unit showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front perspective view of a combination respiratory mask and heat and moisture exchanger unit showing a second embodiment of our new design;

FIG. 9 is a front view thereof;

FIG. 10 is a rear view thereof;

FIG. 11 is a top view thereof;

FIG. 12 is a bottom view thereof;

FIG. 13 is a left side view thereof;

FIG. 14 is a right side view thereof;

FIG. 15 is a front perspective view of a combination respiratory mask and heat and moisture exchanger unit showing a third embodiment of our new design;

FIG. 16 is a front view thereof;

FIG. 17 is a rear view thereof;

FIG. 18 is a top view thereof;

FIG. 19 is a bottom view thereof;

FIG. 20 is a left side view thereof;

FIG. 21 is a right side view thereof;

FIG. 22 is a front perspective view of a combination respiratory mask and heat and moisture exchanger unit showing a fourth embodiment of our new design;

FIG. 23 is a front view thereof;

FIG. 24 is a rear view thereof;

FIG. 25 is a top view thereof;

(Continued)

FIG. 26 is a bottom view thereof;
 FIG. 27 is a left side view thereof; and,
 FIG. 28 is a right side view thereof.

One or more views (e.g., bottom view) may not be shown as those views are unornamented or simply not claimed in a given embodiment.

The broken lines in the drawings depict portions of the combination respiratory mask and heat and moisture exchanger unit that form no part of the claimed design.
